ROTARY DRILL

Application filed September 17, 1927. Serial No. 220,158.

This invention relates to a rotary drill and has particular reference to a drill for use in drilling deep wells, for instance, oil wells, with a rotary method. It is a general object of this invention to provide an effective improved tool of this general character.

It is a primary object of our invention to provide a rotary drilling bit of the disk type which will operate to drill rapidly and efficiently.

It is another primary object of our invention to provide a drill of the character mentioned in which the drill parts proper are subject to little wear and which operates with a minimum amount of wear and strain upon the entire drilling apparatus.

Another and important feature of our present invention is the provision of a bit of the character mentioned in which the cutters are effectively and securely mounted in a manner to project a maximum amount from their carrying or supporting parts.

It is another object of our invention to provide an improved form of mounting bushing for a cutter of a well drilling bit.

It is a further object of our present invention to provide an improved manner of mounting a cutter carrying bushing in the body of a well drilling bit.

The various objects and features of our present invention will be best and more fully understood from the following detailed description of a typical preferred form and application of the invention throughout which description reference is had to the accompanying drawings in which

Fig. 1 is a perspective view of the bit provided by our present invention viewed from one side;

Fig. 2 is a view of the lower end of the bit;

Fig. 3 is an enlarged detail sectional view taken through one of the cutters and its supporting arms;

Fig. 4 is a perspective view of one of the bushing sections provided by our invention viewing the section from its outer or flange end;

Fig. 5 is a perspective view of a bushing section viewed from its inner end; and

Fig. 6 is a sectional view taken at the lower end portion of the shank of the bit showing the water course bushing.

The bit provided by this invention includes, generally, a main body or shank 10, a tapered screw threaded pin 11 at the upper end of the shank for connection with a string of drill pipe, or the like, a plurality of arms 12 and 13 projecting from the lower end portion of the shank, bushings 15 mounted between the arms 12 and 13, pins 16 which operate to hold the bushings in the arms, and disk cutters 17 rotatably carried by the bushings.

The shank 10 is an elongated member preferably round in cross sectional configuration. In the preferred construction the shank has an enlarged portion 18 at its upper end presenting a downwardly facing shoulder 19 to be engaged by a fish tool or suitable device in the event that the bit becomes lost in the well. The tapered screw threaded pin 11 projects upwardly from the enlarged part 18 of the shank and is preferably formed integral with the shank. The shank has a longitudinal circulation opening 60 extending throughout its length. The opening 60 discharges downwardly at the center of the lower end of the shank to impinge upon the inner portions of the cutters and thus aid rotation of the cutters. We provide a replaceable nozzle bushing 61 at the lower end of the opening 60, as shown in Fig. 7 of the drawings.

The arms provided at the lower end of the shank 10 extend downwardly and radially from the lower end portion of the shank and are preferably formed integral with the shank. In practice, we have enlarged the lower end of the shank and machined it to form the desired arms 12 and 13. The arms 12 and 13 are arranged in pairs and in the preferred form of the invention there are three pairs of arms as illustrated throughout the drawings. It is to be understood, of course, that the pairs of arms are equally spaced or symmetrically disposed about the central longitudinal axis of the tool so that the construction is balanced resulting in smooth operation and proper centering of the tool in the hole. The arms 12 and 13 of each

pair are in spaced parallel relation and extend downwardly and radially from the lower end portion of the shank 10. The arms 12 and 13 are pitched or angularly disposed 5 with reference to longitudinal axis of the tool, it having been found that satisfactory results are obtained by pitching the arms at an angle of approximately 45 degrees with reference to the vertical axis of the tool. The 10 arm 13, which is the lowermost arm, has its lower end portion dressed or bevelled off at 20 to provide ample clearance behind the cutter as will appear from Fig. 3 of the drawings. Further, the outer or edge portion 21 of the uppermost arm 12 is preferably finished so that it is substantially vertical to give clearance above the cutter for cuttings and the passage of circulating fluid.

A bushing 15 is mounted between each pair 20 of arms 12 and 13 to carry a cutter 17 so that its cutting or active portion projects downwardly and radially from the arms in the manner shown throughout the drawings. Each bushing 15 has an outer cylindrical bearing part 22 to rotatably carry a cutter and is provided at each end with a radially 25 projecting flange 23 to engage or overhang the front and rear faces of the cutter. The bushing is made to fit closely between the parallel inner faces 25 and 26 of the arms 12 and 13, respectively, in this manner clearly indicated in Fig. 3 of the drawings. The cutter 17 is rotatably carried on the bearing surface 22 of the bushing and fits the end 30 flanges 23 with sufficient working clearance to allow it to turn freely. With this arrangement the flanges 23 operate to space the cutter from the inner faces 25 and 26 of the arms. In the preferred form of the invention, the 35 bushing 15 is carried between the outer end portions of the arms 12 and 13 so that it supports the cutter in position to project a maximum amount beyond the outer portions of the arms. In accordance with our invention, the bushing 15 is stationary or held against 40 movement relative to the arms causing all wear due to rotation of the cutters to occur between the cutters and bushings. In the preferred form of bushing mounting provided by our invention, the bushing is provided at either or both of its ends with ribs or key 45 projections 28 which fit or extend into corresponding recesses or slots provided in the faces 25 and 26 of the arms and the bushing 50 is retained in position between the arms by a pin 16 extending through and between the arms and through an opening 30 extending through the bushing. The axis of the opening 30 is preferably offset or made eccentric 55 to the axis of the bearing surface 22 of the bushing so that the pin 16 can be located as far as possible inward of the outer ends of the arms. The relationing of the bearing surface 22 and pin opening 30 is clearly illustrated 60 in Figs. 3, 4 and 5 of the drawings. It will

be apparent that with this arrangement and formation of parts the pin is effective and reliable in retaining the bushing 15 in place between the arms and is at the same time well removed from the extreme outer ends of the 70 arms 12 and 13, being inward of the pivotal axis of the cutter 17 so that it is firm and secure in the arms. In the particular construction illustrated in the drawings, the pin 16 extends through an opening 31 in 75 the uppermost arm 12 and has its end portion 32 screw threaded into a threaded opening 33 provided in the arm 13. A head 34 is provided on the upper end of the pin to seat against the upper or outer side of the arm 12, 80 as clearly shown in the Fig. 3. With the construction provided by our invention, there is no tendency for the pin to rotate and thus become disengaged from the threaded opening 33 in the arm 13. However, if desired, locking 85 means may be provided in connection with the pin to make it secure. For instance, we have shown a set screw 35 carried by the arm 12 to engage and lock the pin 16.

In the preferred construction of the bushing 15 the key projections 28 on the ends of the bushing are arranged to intersect the pin opening 30 and the grooves provided in the inner faces of the arms for the reception of the key projections 28 extend horizontally or 90 in a radial direction, as shown throughout the drawings. Further, the bushing 15 is divided or formed in two sections to facilitate its application to the cutter 17. In practice, it is preferred that the bushing be divided transversely at a point intermediate to its ends into two sections, each having a bearing portion 22, a flange 23 at its outer end, and a key projection 28.

Each cutter 17 is an annular disk-like member having a central opening 40 to receive a bushing 15. The edge or periphery portion 41 of the cutter is dressed or bevelled off at a suitable angle, preferably at an angle of about 45 degrees, to form a cutting edge 42 with the side 43 of the cutter. The cutter is mounted so that its side 43 faces downwardly or is lowermost, thus bringing the edge 42 in position to effectively cut the formation at the bottom of the hole being drilled. With the arms 12 and 13 disposed at an angle of substantially 45 degrees, the cutter when in operation has its under side 43 pitched upwardly and rearwardly at an angle of substantially 45 degrees while the leading or foremost part of the periphery 41 is substantially vertical.

Having described in detail one pair of arms, one bushing and one cutter, it would be apparent that such description applies likewise to each cutter unit embodied in the bit and how the symmetrical arrangement of the cutters or cutting units provides a balanced, effective and practical drilling tool. Particular attention is called to the fact that the only 130

parts subject to any substantial amount of wear are the cutters and bushings which parts can be easily and quickly replaced. Further particular attention is called to the arrangement of the pin for securing the cutter carrying bushing whereby the cutter is carried to project a maximum amount from the arms while the pin is well removed from the extreme end portions of the arms. This feature of the invention is very important as it provides an effective, sturdy and strong construction.

Having described only a typical preferred form of our invention we do not wish to limit ourselves to the specific details set forth, but wish to reserve to ourselves any changes or variations that may appear to those skilled in the art or fall within the scope of the following claims.

Having described our invention, we claim:

1. A well drilling bit including a shank having a central longitudinal fluid circulation opening discharging downwardly at the center of the lower end of the shank, a plurality of symmetrically arranged pairs of spaced arms projecting downwardly and radially from the lower end portion of the shank and inclined at an angle of substantially forty-five degrees relative to the vertical axis of the bit, a sectional bushing arranged between each pair of arms, each bushing having an exterior bearing surface and an opening the axis of which is offset from the axis of the bearing surface in a direction inward of the outer ends of the arms, a pin in connection with each pair of arms, extending through the opening in the bushing and screw threaded into the lowermost arm, a key projection on each bushing section fitting a complementary transverse recess in an arm whereby the bushing sections are held against turning, and a disk cutter rotatably mounted on each bushing, each cutter having its periphery bevelled so that its leading part is substantially vertical.

2. A well drilling bit for use with the rotary method including, a shank having a fluid circulation opening extending longitudinally through it and discharging downwardly at the center of the lower end of the shank, a plurality of integral arms extending downwardly and radially from the lower portion of the shank and arranged in pairs, a sectional bushing between the arms of each pair, a cylindrical bearing part on each section of the bushings, a pin carried by each pair of arms and extending through the bushing eccentric to the said bearing parts, means preventing rotation of the bushings, and cutters rotatably supported on the said bearing parts, each cutter having a single leading edge engaging the bottom of the hole being drilled, said edge being formed between a surface of the cutter extending upwardly and rearwardly at an angle of substantially forty-

five degrees and a surface that is substantially vertical.

3. A well drilling bit including, a shank, a pair of spaced arms projecting from the shank, a sectional bushing comprising two sections arranged between the arms, each section having an outer cylindrical bearing part, an integral radial flange at the outer end of each section, and a key projection extending completely across the outer end of each flange, a pin carried by the arms and extending through the sections and offset from the axis of said bearing parts, and a disc cutter rotatably carried on the said bearing parts between the flanges having a periphery of such shape that the portion thereof at the lowermost end of the cutter is bounded by a substantially vertical plane, there being transverse recesses in the arms to receive the key projections.

In witness that we claim the foregoing we have hereunto subscribed our names this 30th day of August, 1927.

VAN J. KUBIN.
